(57) **CLAIM**

The ornamental design for a screen for a mobile terminal device, as shown and described.

DESCRIPTION

The file of this patent contains a least one drawing/photograph executed in color. Copies of this patent with color drawings/photographs will be provided by the United States Patent and Trademark Office upon request and payment of the necessary fee.

FIG. 1 is a front, top, and right side perspective view of a screen for a mobile terminal device showing our new design; FIG. 2 is a front view thereof; FIG. 3 is a rear view thereof; FIG. 4 is a top view thereof; FIG. 5 is a bottom view thereof; FIG. 6 is a right side view thereof; and, FIG. 7 is a left side view thereof.

The broken lines shown in the figures illustrate portions of the mobile terminal device that form no part of the claimed design.
